(57) **CLAIM**

The ornamental design for a pet chew as shown and described.

DESCRIPTION

FIG. 1 is a perspective view of a pet chew showing my new design according to a first embodiment;

FIG. 2 is another perspective view thereof according to the first embodiment;

FIG. 3 is a front view thereof according to the first embodiment;

FIG. 4 is a rear view thereof according to the first embodiment;

FIG. 5 is a left view thereof according to the first embodiment;

FIG. 6 is a right view thereof according to the first embodiment;

FIG. 7 is a top view thereof according to the first embodiment;

FIG. 8 is a bottom view thereof according to the first embodiment;

FIG. 9 is a perspective view of a pet chew showing my new design according to a second embodiment;

FIG. 10 is another perspective view thereof according to the second embodiment;

FIG. 11 is a front view thereof according to the second embodiment;

FIG. 12 is a rear view thereof according to the second embodiment;

FIG. 13 is a left view thereof according to the second embodiment;

FIG. 14 is a right view thereof according to the second embodiment;

FIG. 15 is a top view thereof according to the second embodiment; and,

FIG. 16 is a bottom view thereof according to the second embodiment.

The break lines shown in the middle portion of the pet chew in FIGS. 1-4, 7-12, 15 and 16 indicate that the appearance of any portion of the article between the break lines form no part of the claimed design.

1 Claim, 16 Drawing Sheets

Related U.S. Application Data

application No. 29/869,731, filed on Jan. 6, 2023, said application No. 29/910,826 is a continuation-in-part of application No. 29/867,232, filed on Oct. 14, 2022.
